DESIGN FOR A REFLECTOR

John H. Waterbury, Chicago, Ill., assignor to
Benjamin Electric Mfg. Company, Des Plaines,
Ill., a corporation of Illinois

Application January 17, 1934, Serial No. 50,428

Term of patent 14 years

To all whom it may concern:

Be it known that I, JOHN H. WATERBURY, a citizen of the United States, residing at Chicago, in the county of Cook and State of Illinois, have invented a new, original, and ornamental Design for a Reflector, of which the following is a specification, reference being had to the accompanying drawing forming a part thereof, in which:

Figure 1 is a side elevational view of the reflector; and

Fig. 2 is an elevational view from the right of Figure 1.

I claim:

The ornamental design for a reflector, substantially as shown.

JOHN H. WATERBURY.
